(57) **CLAIM**

The ornamental design for digital multifunction printer, as shown and described.

DESCRIPTION

FIG. 1 is a front view of a digital multifunction printer showing our new design;

FIG. 2 is a rear view of the digital multifunction printer;

FIG. 3 is a top plan view of the digital multifunction printer;

FIG. 4 is a bottom view of the digital multifunction printer;

FIG. 5 is a right view of the digital multifunction printer;

FIG. 6 is a left view of the digital multifunction printer; and,

FIG. 7 is a perspective view of the digital multifunction printer.

The evenly spaced broken lines shown in the drawings represent portions of the digital multifunction printer that form no part of the claimed design.

1 Claim, 7 Drawing Sheets
